UNITED STATES PATENT OFFICE.

WILFRED T. BIRDSALL, OF MONTCLAIR, NEW JERSEY, ASSIGNOR, BY MESNE ASSIGNMENTS, TO WESTINGHOUSE ELECTRIC & MANUFACTURING COMPANY, A CORPORATION OF PENNSYLVANIA.

COMPRESSION-TYPE SEAL.

1,184,813.

Specification of Letters Patent. Patented May 30, 1916.

Application filed May 4, 1915. Serial No. 25,865.

To all whom it may concern:

Be it known that I, WILFRED T. BIRDSALL, a citizen of the United States, and a resident of Montclair, in the county of Essex and State of New Jersey, have invented a new and useful Improvement in Compression-Type Seals, of which the following is a specification.

My invention relates to seals between substances having different coefficients of linear expansion, and it has for its object to provide a device of the character described that will be simple, inexpensive and rugged in construction.

Referring to the accompanying drawing, Figure 1 is a side view, partially in section and partially in elevation, of a seal embodying my invention; and Figs. 2 and 3 are plots illustrating and indicating the relation of the different coefficients of expansion in my seal.

Hitherto, when it has been desired to introduce electric current into evacuated containers of vitreous material, it has been necessary to fuse the conductor to the wall and the material which has been used with most success as a sealing-in conductor has been platinum. When it is desired to employ platinum, however, in large amounts, as is necessary for large-capacity rectifiers, its cost becomes prohibitive.

I have found, by surrounding a leading-in wire of any material, such, for example, as iron or tungsten by a mass of elastic material such, for example, as glass, and by surrounding said glass by a band of material having high tensile strength, said band of material being shrunk on so that the mass of glass is at all times maintained under compression, I am enabled to provide, in different annular zones of the glass, apparent coefficients of expansion which vary uniformly from that of the wire to that of the surrounding band. By choosing, therefore, a compressing band the coefficient of expansion of which, with respect to the coefficient of the wire, lies beyond the coefficient of the material in the container, I am enabled to provide a zone of glass having an apparent coefficient which is substantially that of the container and, by fusing the container wall to said zone in any well known manner, I am enabled to obtain a

vacuum-tight joint between the container wall and the leading-in wire, in spite of great divergencies in the coefficients of expansion therebetween.

Referring to the accompanying drawings for a more detailed understanding of my invention, I have shown a leading-in wire 4 at 4 in Fig. 1. The leading-in wire 4 is surrounded by, and supports, a mass of elastic material 5 formed, preferably, of glass. A band of material 6 surrounds the body of glass 5 and is formed of material having high tensile strength, such, for example, as steel or brass. The band 6 is shrunk upon the body of glass 5 and is of such tensile strength that it will maintain the body in a state of compression throughout a wide range of temperature variation. Under these conditions, the body 5 will not follow the ordinary law under which all of its component portions would exhibit the same coefficient of linear expansion, but the zone lying adjacent to the wire 4 will be forced to assume an apparent coefficient of expansion closely approximating to that of the wire 4. In like manner, the zone of the mass 5 lying adjacent to the band 6 will be forced to assume an apparent coefficient of expansion closely approximating that of the material composing the band 6. All zones lying between the wire 4 and the band 6 will exhibit different apparent coefficients of expansion, there being a gradual transition from the value exhibited adjacent the wire 4 to the value exhibited adjacent the band 6. The neck of the container of a vapor electric device is shown at 7, and the coefficient of the band 6 is so chosen with respect to the coefficient of the wire 4 that it lies beyond the coefficient of the material composing the container 7. For example, if the material of the container 7 has a lower coefficient than that of the wire 4, the material of the band 6 will be chosen to have a still lower coefficient, and vice versa. As there is a gradual transition in the body 5 from an apparent coefficient approximating that of the wire 4 to that approximating the coefficient of the band 6, a certain zone will be found having an apparent coefficient of expansion closely approximating that of the material of the container 7. If the container 7 is fused to

105

this zone, there will be no differential expansion tending to rupture the seal, and a vacuum-tight connection may be readily provided between the container 7 and the wire 4.

In order to compute the necessary radius for the neck of the container 7 to satisfy the above-described conditions, recourse may be had to a simple graphic treatment, as 10 illustrated in Figs. 2 and 3. Let the distances CD and CF be laid out on an ordinate to correspond, respectively, to the radii A and B of the wire 4 and of the inner surface of the band 6 at any arbitrary temperature. 15 In like manner, let the distances GH and GK represent the respective radii of said two members at a different temperature. Connect the points F and K and D and H, respectively, and let said lines be extended 20 to a point of intersection, such as M. The steepness of the line DH will then be a measure of the coefficient of expansion of the material of the wire 4 and the steepness of the line F will be a measure of the coefficient of the material of the band 6. Construct a line MJ passing through the point 25 M and having a steepness corresponding to the coefficient of the material of the container 7 to the same scale as has been used in plotting the coefficients of the members 30 4 and 6. The line MJ will intercept the ordinate DF at a point E and the distance CE will be the desired radius X for the neck of the container 7 to the proper scale. To 35 prove this, consider a particle in the mass 5 lying at distance X from the wires. If the mass 5 is homogeneous, as must be assumed, this particle will always divide the distance between the wire and the outside 40 band in the same ratio. In Fig. 2 we measure this distance as DF. Then we know by geometry that any line drawn through M will divide similar lines, such as HK, in the same ratio that it divides DF. If the radius 45 X is CE in Fig. 2, it follows that points of intersection with the different ordinates by the line MJ will give the radii of the particle of glass under compression at the temperatures respectively corresponding on the 50 diagram to each ordinate. But the position of the line MJ is bound to indicate the radius of the neck of the container 7 at each temperature. It will also indicate the position of the particle of the mass 5 at all temperatures and the coefficient of the zone in 55 the mass 5 at the radius X must be the same as that of the container 7. It therefore follows that a tube the mean radius of which is determined as above can be sealed directly 60 to the wire 4 without danger of rupture.

If a seal is to be made without the central wire 4, then, in Fig. 2, the line MDH will be omitted and the point M will become the intersection of the line FK with the horizontal axle.

In the specific case when the wire 4 and the band 6 have the same coefficient, the point M will lie at infinity and, since the line MEJ must pass through this point, it would be parallel with FK and DH in each case. That is, the coefficient of the container 7 must be the same as that of the wire and of the band.

Referring to the diagram shown in Fig. 3, the conditions are exactly the same as 75 shown in Fig. 2 except that the coefficient of the band 6 is less than that of the wire 4 and, accordingly, the computation must be made on opposite sides of the point of intersection. Particular attention should be 80 paid to the fact that the values of the coefficients of the wire and of the clamping band should always be so chosen that they lie on opposite sides of the coefficients of the material of the container.

While, throughout this case, I have described the band 6 as being composed of metal, it may very well be composed of glass or of any other material having suitable properties.

I have described the external band 6 as exerting pressure upon the mass 5 but, within certain limits determined by the coherence of the joints, the member 6 may exert tension on the mass of the member 5, establishing forced coefficients of expansion in the intermediate zones thereof in the same manner as under conditions of pressure.

Many materials, such, for example, as compound metals, have an expansion line 100 which is curved or which comprises two relatively straight lines meeting at an angle. If the seal is raised to a temperature where the external forces acting upon the intermediate mass 5 are modified, the different zones 105 will obey new laws, following an expansion line between the lines of the members 4 and 6. If either the member 4 or the member 6 entirely ceases to act upon the mass 5, the intermediate zones of the latter will follow 110 other laws, the apparent coefficient being raised if the wire 5 first releases and being lowered if the band 6 is the first to cease 115 operation.

With certain combinations of materials, 120 a seal having excellent manufacturing characteristics, such, for example, as cheapness, ease of manipulation, and great mechanical strength, may be produced in accordance with my invention but may exhibit a tendency to develop minute leaks. By sealing these leaks with suitable gums, shellacs, or like substances, a highly effective device may be produced.

While I have disclosed my invention in 125 its preferred form, it will be obvious to those skilled in the art that it is susceptible of various minor changes and modifications without departing from the spirit thereof and I desire, therefore, that no limitations 130

shall be placed thereupon except such as are imposed by the prior art or are specifically set forth in the appended claims.

I claim as my invention:

5. 1. A seal between two members having different coefficients of expansion which comprises a third member having a plurality of different forced coefficients of expansion in different zones thereof, and a seal 55 between each of said first named members and a zone of like coefficient to its own. 60
10. 2. A seal between a tubular member and a wire extending therethrough and having a different coefficient of expansion therefrom comprising a mass of material having a plurality of different forced coefficients of expansion in different zones thereof, a seal between said wire and a zone of said mass of corresponding coefficient, and a seal between 15 said tubular member and a zone of said mass of corresponding coefficient. 65
15. 3. In a seal, the combination with two members between which a tight connection is to be made, of a third member, means for forcing said third member into close contact with one of said first named members and for imposing upon different portions of said third member different apparent coefficients of expansion, and means for attaching the other of said first named members to a portion of said third member corresponding to its own coefficient of expansion. 70
20. 4. A seal between a tubular member and a wire extending therethrough and having a different coefficient of expansion therefrom comprising a mass of material surrounding said wire, means for forcing said mass into intimate contact with said wire and for causing the outer portion of said mass to assume 75 different coefficients of expansion such that the coefficient of the tubular member is between those of the wire and of the outer portion of said mass, and a seal between said tubular member and an intermediate zone in said mass having a coefficient of expansion corresponding to its own. 80
25. 5. The combination with a wire, of a mass of elastic material mounted thereupon, a clamping member surrounding said mass and forcing the portions thereof adjacent 85
30. said wire to assume a coefficient of expansion similar to that of the wire while forcing annular zones in said mass of larger radius from said wire to assume coefficients of expansion differing by continuously increasing amounts from that of the wire, and a tubular member having a coefficient of expansion differing from that of the wire and sealed to a zone in said mass having a coefficient corresponding to its own. 90
35. 6. The combination with a wire, of a mass of glass mounted thereupon, a metallic band shrunk around said mass of glass so that said mass is maintained in compression throughout a wide temperature range and is forced to assume apparent coefficients of expansion in the portions adjacent to said wire and to said band of values corresponding, respectively, to those of the wire and band and in intermediate zones to assume 95 apparent coefficients of expansion of intermediate values, and a member composed of material having a coefficient between those of the wire and of the band and sealed to a portion of said mass having a coefficient corresponding to its own. 100
40. 7. The method of joining two members having different coefficients of expansion which comprises imposing upon different portions of a third member a plurality of different apparent coefficients of expansion, and sealing each of said first named members to a portion of said third member having a coefficient corresponding to its own. 105
45. 8. The method of joining two members having different coefficients of expansion which comprises imposing upon different portions of a third member of elastic material a plurality of different apparent coefficients of expansion by continuously applied external force and sealing each of said first named members to a portion of said third member having an apparent coefficient corresponding to its own coefficient. 110
50. In testimony whereof, I have hereunto 115 subscribed my name this 28th day of April, 1915.

WILFRED T. BIRDSALL.
